CLAIM

The ornamental design for a smokeless firepit, as shown and described.

DESCRIPTION

FIG. 1 is a perspective view of a smokeless firepit;

FIG. 2 is a front view of the smokeless firepit of FIG. 1;

FIG. 3 is a rear view of the smokeless firepit of FIG. 1;
FIG. 4 is a left side view of the smokeless firepit of FIG. 1;
FIG. 5 is a right side view of the smokeless firepit of FIG. 1;

FIG. 6 is a top view of the smokeless firepit of FIG. 1;
FIG. 7 is a bottom view of the smokeless firepit of FIG. 1;
FIG. 8 is a perspective view of a smokeless firepit with a grill grate attachment shown in environmental lines;
FIG. 9 is a front view of the smokeless firepit of FIG. 8;
FIG. 10 is a rear view of the smokeless firepit of FIG. 8;
FIG. 11 is a left side view of the smokeless firepit of FIG. 8;

FIG. 12 is a right side view of the smokeless firepit of FIG. 8;

FIG. 13 is a top view of the smokeless firepit of FIG. 8;
FIG. 14 is a bottom view of the smokeless firepit of FIG. 8;
FIG. 15 is a perspective view of a smokeless firepit with a rotisserie attachment shown in environmental lines;
FIG. 16 is a front view of the smokeless firepit of FIG. 15;
FIG. 17 is a rear view of the smokeless firepit of FIG. 15;
FIG. 18 is a left side view of the smokeless firepit of FIG. 15;

FIG. 19 is a right side view of the smokeless firepit of FIG. 15;

FIG. 20 is a top view of the smokeless firepit of FIG. 15;
FIG. 21 is a bottom view of the smokeless firepit of FIG. 15;
FIG. 22 is a perspective view of a smokeless firepit with a heat shield attachment shown in environmental lines;

FIG. 23 is a front view of the smokeless firepit of FIG. 22;
FIG. 24 is a rear view of the smokeless firepit of FIG. 22;
FIG. 25 is a left side view of the smokeless firepit of FIG. 22;

FIG. 26 is a right side view of the smokeless firepit of FIG. 22;

FIG. 27 is a top view of the smokeless firepit of FIG. 22;
and,

FIG. 28 is a bottom view of the smokeless firepit of FIG. 22.
In the drawings, the broken lines depict environmental subject matter only and form no part of the claimed design.
The broken lines shown on the front of the firepit shown in FIGS. 1, 2, 4, 5, 8, 9, 11, 12, 15, 16, 18, 19, 22, 23, 25 and 26 indicate the boundaries and form no part of the claimed design.
